(57) **CLAIM**

The ornamental design for a monitor, as shown and described.

DESCRIPTION

FIG. 1 is a front perspective view of the monitor showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another front perspective of the monitor of FIGS. 1-7, shown in an environment of use with the environmental strap attached;

FIG. 9 is another front perspective view of the monitor of FIGS. 1-7, shown in an alternate, fully expanded, configuration of use;

FIG. 10 is a front view of FIG. 9;

FIG. 11 is a rear view of FIG. 9;

FIG. 12 is a left side view of FIG. 9;

FIG. 13 is a right side view of FIG. 9;

FIG. 14 is a top plan view of FIG. 9; and,

FIG. 15 is a bottom plan view of FIG. 9.

The broken lines depict portions of the monitor that form no part of the claimed design.

1 Claim, 15 Drawing Sheets
